UNITED STATES PATENT OFFICE.

SAMUEL N. HOUSE, OF ST. LOUIS, MISSOURI.

TENON-CUTTER.

1,149,581.

Specification of Letters Patent. Patented Aug. 10, 1915.

Application filed September 24, 1914. Serial No. 863,274.

To all whom it may concern:

Be it known that I, SAMUEL N. HOUSE, a citizen of the United States of America, and a resident of the city of St. Louis and State of Missouri, have invented certain new and useful Improvements in Tenon-Cutters, of which the following is a full, clear, and exact description, reference being had to the accompanying drawings, forming a part of 10 this specification.

My invention relates to a tenon cutter for forming tenons at the ends of wheel spokes or other articles, one of the objects being to produce a very strong tool of this kind 15 which is well adapted to resist the severe twisting stresses to which it is subjected in service.

With this object in view, the tenon cutter preferably comprises a skeleton main frame 20 having parallel guide members adjacent to its sides, a slideable abutment jaw and a slideable knife carrying jaw, both of which extend across the main frame. To secure the desired strength the guide members at the 25 sides of the skeleton main frame are securely connected to each other by one or both of the slideable jaws which extend across the main frame. Prior to this invention tenon cutters have been provided with a main 30 frame having guide members adjacent to its sides and jaws slideably fitted to such guide members, but in so far as I am aware it is new to reinforce the skeleton main frame of a tenon cutter by utilizing the slideable jaws 35 as means for connecting the opposite side portions of said skeleton main frame.

Figure I is a side elevation of a tenon cutter embodying the features of my invention. Fig. II is an inverted plan view of the 40 tenon cutter. Fig. III is a vertical section. Fig. IV is a transverse section taken approximately on the line IV-IV, Fig. I.

The principal elements of the tenon cutter I have shown are the skeleton main frame 45 A, a knife carrying jaw B, an abutment jaw C, both of said jaws being slideably fitted to the main frame, and a screw D for moving said jaws toward and away from each other.

The main frame A preferably comprises 50 a pair of legs 1 and 2 separated from each other to receive the tenon at the end of a spoke or other article, and integrally connected together at their upper ends.

4 designates a non-circular stem secured to the upper end of the main frame and 55 adapted to fit into a rotatable socket 5 which may be operated in any suitable manner:

The legs 1 and 2 are provided with arched portions 6 which connect said legs near their lower ends, as shown most clearly in Fig. 60 IV. The legs 1 and 2 are integrally connected to side bars 7 which form part of the skeleton main frame, and which are united by a substantially U-shaped yoke 8 formed integral with said bars. Each side bar 7 is 65 provided with a pair of ears 9 for the reception of a rigid guide rod 10, the ends of said guide rod being firmly secured to said ears 9. The guide rods 10, located adjacent to the opposite sides of the main frame, are 70 parallel with each other and it may be stated that these guide rods form part of the main frame.

The abutment jaw C comprises an abutment member 12 extending transversely of the main frame, and having a V-shaped pocket for the reception of the tenon which is formed by cutting away a portion of a wheel spoke or other article. Tubular slide members 13, at the ends of the abutment 75 member 12, surround the guide rods 10 and are closely fitted thereto so that the guide rods are connected by the abutment member 12. The abutment jaw C is also provided with a yoke 14 which extends toward the 80 yoke 8 of the main frame, as shown most clearly in Fig. II.

The knife carrying jaw comprises a knife holding member 15 extending across the main frame and provided with tubular slide 90 members 16, which surround the guide rods 10. These tubular slide members 16, like the corresponding parts of the abutment jaw 12, are closely fitted to the guide rods.

15 designates a yoke preferably formed 95 integral with the knife carrying jaw B, said yoke being located back of the abutment member 12.

17 designates a knife blade secured to the knife carrying jaw B in a manner hereinafter described.

The adjusting screw D has a reduced neck 18 so journaled in the main frame as to prevent movement of said adjusting screw longitudinally of the main frame. The adjusting screw has a right hand screw thread 19

operable in the yoke of the knife carrying jaw, and a left hand thread 20 operable in the yoke of the abutment jaw. Both of the jaws being slidably fitted to the 5 guide rods 10, rotation of the adjusting screw D results in moving said jaws toward and away from each other.

21 is a set screw carried by the abutment jaw C and adapted to engage the guide rods 10 to prevent movement of the jaws on the guide rods after they have been adjusted to the desired positions.

In cutting the tenon the article to be operated upon is cut by the knife 17 and the 15 tenon after being formed by the knife passes between the jaws B and C and enters between the legs 1 and 2 of the main frame A to engage an adjustable stop 22 arranged between the legs 1 and 2, the stop being secured to the leg 1 by means of a screw 23 passing through a slot in said leg.

When the tenon cutter is in service the skeleton main frame is rotated and the abutment jaw and knife carrying jaw, which 25 must turn with the skeleton main frame, are firmly engaged with the work. Therefore, the skeleton main frame is subjected to severe twisting strains, and, as previously pointed out, one of the objects of my invention 30 is to provide a tenon cutter which is well adapted to resist such strains. If the slideable jaws were merely interposed between the guide members at the sides of said skeleton main frame, instead of being actually connected to said guide members, the twisting strains referred to would tend to spread the sides of the main frame away from each other. In accordance with my invention the guide rods 10, forming part of 40 the main frame, are actually connected to each other by one or both of the slideable jaws. The side portions of the main frame are positively prevented from moving away from each other when the tool is in service, 45 and the entire main frame is, therefore, very materially reinforced by the slideable jaws B and C.

To insure the desired cutting action, the cutting edge of the knife blade 17 must lie 50 horizontally, or in other words the plane of the cutting edge should be at a right angle to the axis of the tenon, and since the knife blade must be removed and sharpened from time to time it has heretofore been quite difficult to locate the cutting edge in the desired plane. The knife I have shown is fitted to the knife holder 15 and secured thereto by means of a bolt 25 passing through the middle portion of the knife and passing 55 through a slot 26 in the knife holder 15. The head of the bolt 25 is seated on a block 27 and a nut 28 screwed onto the threaded end of the bolt is adapted to bear against the knife holder 15. The means for adjusting 60 the knife blade to locate its cutting edge in

the desired plane comprises a pair of adjusting screws 29 screwed into the knife holder at points adjacent to the opposite side edges of the knife blade (Fig. II), and engaging the inner face of said knife blade. The knife blade may be tilted by turning either of the screws 29 and after the desired adjustment has been obtained the knife blade may be firmly clamped onto the inner ends of said adjustment screws by turning the nut 28 on the connecting bolt 25, which passes through the middle portion of the knife blade. To afford a more complete understanding of the merits of the peculiar means for adjusting the knife blade of my tenon cutter it should be stated that said blade is inclined slightly, in the usual manner, so that its cutting edge will engage the work to form a shoulder thereon, while the broad outer face of the blade will clear the shoulder formed at said cutting edge. The tool is intended to be used in cutting tenons of different dimensions on spokes of different dimensions, and in practice the cutting edge of the blade near the point 17' (Fig. II) is in service in all cutting operations, while the remaining portion of the cutting edge is not in service in all cutting operations. Therefore, in practice the blade is rapidly worn away near its point 17' by frequent cutting and sharpening while the remaining portion of the blade is not subjected to a like degree of wear by the cutting and sharpening operations. Owing to the inclination of the blade it must be tilted in its holder when the cutting edge is worn away near the point 17', and the screws 29 may be readily adjusted to locate the cutting edge in the desired plane.

I claim:

1. A tenon cutter comprising a main frame provided with side members, guide rods the ends of which are rigidly fixed to said side members, an end member in the form of a yoke integrally connected to said side members and forming part of said main frame, an abutment jaw comprising an abutment member extending across the main frame and surrounding said guide rods, a substantially U-shaped yoke formed integral with said abutment member; a knife carrying jaw comprising a knife holder extending across said main frame and surrounding said guide rods, a substantially U-shaped yoke formed integral with said knife carrying jaw, and an adjusting screw journaled in the end member of said main frame and screwed into the yokes of said jaws.

2. A tenon cutter comprising a main frame provided with a stem at one of its ends and a pair of guide rods at its opposite end, said guide rods being arranged at right angles to the axis of the tenon cutter, a knife carrying jaw and an abutment jaw extending across said main frame and slid-

ably fitted to said guide rods, said slideable jaws being arranged on opposite sides of the axis of the tenon cutter and adapted to firmly engage opposite sides of the work, each of said guide rods being surrounded by and closely fitted to both of said jaws, so that the latter serve as means for connecting

said guide rods at points on opposite sides of said axis, and means for adjusting said jaws.

S. N. HOUSE.
